(57) **CLAIM**

The ornamental design for a container attachable to a bicycle rack, as shown and described.

DESCRIPTION

FIG. 1 is a top perspective view of a container attachable to a bicycle rack embodying my new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof;

FIG. 8 is a bottom perspective view thereof; and,

FIG. 9 is a perspective view thereof as installed on an exemplary bicycle.

The broken lines shown in the drawings represent subject matter that form no part of the claimed design.
